UNITED STATES PATENT OFFICE.

MILTON DURNELL AND ELISHA BEETS, OF GREENFIELD, OHIO; SAID DURNELL ASSIGNOR TO SAID BEETS.

PORTABLE GRATE-SHELF.

SPECIFICATION forming part of Letters Patent No. 309,445, dated December 16, 1884.

Application filed January 3, 1884. (No model.)

To all whom it may concern:

Be it known that we, MILTON DURNELL and ELISHA BEETS, of Greenfield, in the county of Highland and State of Ohio, have invented 5 certain new and useful Improvements in Portable Grate-Shelves; and we do hereby declare that the following is a full, clear, and exact description thereof, reference being had to the accompanying drawings, and to the letters of 10 reference marked thereon, which form part of this specification, in which—

Figure 1 is a perspective view of our improved grate rack or shelf. Fig. 2 is a transverse section of the same.

15 This invention relates to a grate rack or shelf which is portable, and so constructed that it will afford a substantial support for andirons, sad-irons, coffee-pots, or any other articles to be heated or kept warm; and it consists in the new article of manufacture, which 20 will be fully understood from the following description, when taken in connection with the annexed drawings.

The new article of manufacture which we 25 are about to describe consists, essentially, of a shelf, A, which is the segment of a circle, and is ribbed at a. This shelf is re-enforced by radial wires, which we shall now letter in the following manner: The wires which are beneath the shelf are lettered d. These wires 30 are the main supports for the horizontal portion A. The ends e of the wires are turned up, and then bent to form hooks d', and the ends e of said wires are turned down to form legs 35 or auxiliary supports or standards.

It will be seen that the shelf A is constructed entire with upwardly-bent fins or guards B, which may be angular, (or V-shaped;) or they 40 may be of any other shape. These fins or guards are designed to serve, in combination with the bracing-wires above referred to, as stiffeners and auxiliary supports for the shelf A.

It is obvious that the shelf and its fins or guards B are sustained, when attached to a grate, by the wires, as described, and that the 45 fins or guards serve in a great measure to prevent the articles supported on the shelf from being smoked. At the same time the said articles may be highly heated.

This new article of manufacture is adapted 50 for any well-known grate by reason of its hooks, braces, supports, and the shelf.

We are aware that sad-iron shelves have been used before our invention which were adapted to hook on an open grate; but such 55 shelves were constructed of cast-iron, with hooks and handle entire, and were heavy and expensive to make. We therefore disclaim such shelves. Our improved shelf is made of thin wrought metal, braced and strengthened 60 by transverse rods bent and secured to the shelf in such manner that they afford hooked supports and legs, the back of the shelf being provided with fins and guards, which also strengthen and stiffen the shelf. 65

Having described our invention, we claim 65 as new—

The new article of manufacture consisting of a segmental portable grate rack or shelf having formed on it fins or guards, and braced 70 or re-enforced by wires which are bent to form suspending hooks and standards, substantially as described.

In testimony that we claim the foregoing as our own we affix our signatures in presence of 75 two witnesses.

MILTON DURNELL,
ELISHA BEETS.
